UNITED STATES PATENT OFFICE.

LOUIS E. STEINMAN, OF CINCINNATI, OHIO.

DESIGN FOR SIDEBOARDS.

Specification forming part of Design No. 7,812, dated October 27, 1874; application filed June 3, 1874.
 [Term of Patent 7 years.]

To all whom it may concern:

Be it known that I, LOUIS E. STEINMAN, of Cincinnati, in the county of Hamilton and State of Ohio, have invented a new and original Design for a Sideboard, of which the following is a specification:

My improved sideboard is fully represented in the accompanying photograph.

The paneled doors at the base of the sideboard have ornaments A thereon. At each side of the mirror E are closets D D', having doors B B', with beveled panels slightly convex at top and surmounted by cornices C C', ornamented in the manner shown. Panels and other ornaments H are located immediately around the mirror. Over the mirror is an entablature, F, and surmounting this the ornament G.

I claim as new—

The sideboard having ornaments A on paneled doors at the base, the closets D D', having doors B B' with beveled panels slightly convex at top and surmounted by cornices C C', the panels and other ornaments H immediately around the mirror, and the entablature F, surmounted by the ornament G, all substantially as herein shown and described.

In testimony of which invention I hereunto set my hand.

LOUIS E. STEINMAN.
